GARMENT HANGER

Tudy Kamerman, 2808 Michigan Blvd., Racine, Wis.

Filed Oct. 14, 1963, Ser. No. 76,970

Term of patent 14 years

(Cl. D80—8)

FIG. 1

FIG. 2

FIG. 1 is a front elevational view of a garment hanger embodying my new design.

FIG. 2 is a left side elevational view of FIG. 1.

FIG. 3 is a sectional view taken along the line 3—3 of FIG. 1.

The rear of the garment hanger is substantially the same as the front shown in the drawing.

I claim:

The ornamental design for a garment hanger, substantially as shown and described.
